UNITED STATES PATENT OFFICE.

GEORGE FUSSELL, OF PHILADELPHIA, PENNSYLVANIA.

VACUUM MEANS FOR HOLDING TYPE AND MUSIC SHEETS UPON PRINTING PRESSES.

1,426,471.

Specification of Letters Patent. Patented Aug. 22, 1922.

Application filed December 27, 1920. Serial No. 433,329.

To all whom it may concern:

Be it known that I, GEORGE FUSSELL, a citizen of the United States, and a resident of Philadelphia, in the county of Philadelphia and State of Pennsylvania, have invented an Improvement in Vacuum Means for Holding Type and Music Sheets upon Printing Presses, of which the following is a specification.

10 My invention relates to printing presses of the character employed in printing upon music or record sheets for mechanical music players such data as is usually printed thereon, and more particularly to the means 15 for attaching and holding the type sheet or type supporting web and music or record sheet upon the printing head and platen, respectively of such machines.

One means employed heretofore for attaching the type sheets to the printing head of such a machine has been to make the sheet of greater width than the head and secure it thereto by clamping means. When such means is employed it is necessary to 25 stretch the sheet as tightly as possible across and in contact with the surface of the head, and it not infrequently happens that the sheet bearing the type is torn; also it very frequently is the case that some portion of 30 the type sheet will sag so that as the type is being inked the sagged portion of the sheet is likewise inked, with the result that a splotch is made upon the music sheet and the latter possibly spoiled.

35 It is the object of my invention to provide means whereby both the type sheets and music sheets or records may be held at all times close against the surfaces of the type head and platen, respectively.

40 A further object of my invention is to provide means for producing a vacuum adjacent the rear or underneath sides of the type sheets and music sheets or records whereby the atmospheric pressure upon the 45 outer sides thereof forces the said sheets firmly and closely against the surfaces of the printing head and of the platen, respectively.

A further object of my invention is to 50 provide means whereby sections of type sheet may be held upon the printing head.

This is desirable in view of the fact that the type sheet may, by reason of the absorption of moisture or from some other cause, expand so that its length would not correspond to that of the music sheet onto which the data of whatever character desired is to be printed. Should this happen, it would be necessary that one or more short sections be removed from the type sheet in 60 order to reduce it to a length corresponding to that of the music sheet or to the space on the music sheet within which the printing is to be effected.

A still further object of my invention is 65 to provide means whereby type sheets and printing sheets of different lengths may be quickly and easily secured in place upon the printing head and platen, respectively.

A further general object of my invention 70 is to provide means whereby the placing and securing of the type and music sheets upon the printing head and platen, respectively, of a printing press may be greatly facilitated and the time for effecting the 75 same greatly reduced.

I shall not attempt at this point to set forth all of the various objects and advantages of and incident to my invention, but other objects and advantages of the 80 same will be pointed out in the detailed description thereof which follows or will be apparent from such description.

In order that my invention may be more readily understood and its practical advantages fully appreciated, reference should be had to the accompanying drawings in which I have illustrated one embodiment of the same. However, it will be understood that my invention is susceptible of embodiment in other forms of construction than that shown and that changes in the details thereof may be made within the scope of the 90 claims without departing therefrom.

In the drawings:

Fig. 1 is a transverse sectional view of a printing press for printing music sheets for player pianos and the like embodying my invention;

Fig. 2 is a plan view of a portion of a 100 printing head pad;

Fig. 3 is a view partly in side elevation

and partly in longitudinal section of a portion of a printing head provided with means embodying my invention;

5 Fig. 4 is a view in perspective and in dia-
grammatic form showing a printing head
and a platen provided with my invention;

Fig. 5 is a perspective sectional view of
a printing head provided with my invention;

10 Fig. 6 is a top plan view of a platen pro-
vided with means for holding a music sheet
thereon; and

Fig. 7 is a view in elevation of a member
constituting a detail of the construction.

15 Referring to the drawings: 1 and 2 designate
the opposite sides of the printing head
and 3 a flooring or sheathing of wooden
boards or planks or other suitable material
extending between the sides and connected
thereto.

20 This flooring constitutes the base
or support for the pads 4 of sponge rubber
secured thereto, upon which the type sheet
5 of paper or other suitable flexible material
is held. A number of these rubber pads are
25 secured to the under side of the base or floor

30 3 and are arranged end to end entirely cov-
ering the said flooring or sheathing. The said
pads are each of a width of approximately
eleven and one-quarter inches and prefer-
ably should be from five to six feet long.
35 The abutting ends are permanently secured
together by any suitable means, such as rub-
ber cement. Extending transversely of the
said pads are shallow narrow grooves 7
35 which terminate at their opposite ends in
relatively deep grooves 8 which are situated
adjacent the opposite edges of the pads and
which extend lengthwise thereof. Com-
municating with the outer edges of the
40 grooves 8 are short grooves 10 which are
separated by portions 11 of the rubber. A
series of holes 12 extend through the rubber
sheets from the bottom of the grooves 8, the
said holes terminating upon the opposite
45 sides of the pad 4 and being in communica-
tion with the conduits or passageways 15
extending longitudinally of the opposite
sides 1 and 2 of the printing head.

50 In order to provide for the holding of
type sheets 5 of different lengths upon the
printing press head and against the lower
side or surface of the sponge rubber pads 4,
the continuity of the conduits 15 may be in-
terrupted by means of closures or stops 17.

55 It is understood that the printing heads for
printing music sheets for mechanical musi-
cal players such as player pianos in many
cases are of relatively great length, being
in some cases as much as one hundred and
60 seventy-five to two hundred feet long. This
length is required when it is desired to print
a music sheet of corresponding length. In
many cases, however, the music sheets to be
printed are of considerably less length. In
65 such case it is desirable that a printing head

such as that above referred to of much
greater length may be employed readily for
the purpose. It is for this reason that the
conduits 15 are interrupted by means of the
closures or stops 17.

70 For the purpose of withdrawing the air
from the conduits 15 I have provided a cen-
tral pipe or tube 18 provided at intervals
with branches 20 in the form of T's having
oppositely projecting portions 21 with which
75 are adapted to be engaged the ends of rub-
ber tubes 22, the opposite ends of which en-
gage the outer ends of pipes 23 which are
in communication with openings or passage-
ways 24 extending down through the sides 80
1 and 2 of the printing head and the lower
ends of which are in communication with
the conduits 15. Any suitable means, as for
instance a vacuum pump, (not shown) may
be employed for exhausting the air from the
85 central pipe or tube 18, and by means of
the branch pipes comprising the parts 21,
22, 23 and 24, the air may likewise be ex-
hausted from the conduits 15, creating a
partial vacuum therein.

90 The pipe or tube 18 is adapted to be closed
at intervals in proper relation to the clo-
sures or stops 17 in the conduits 18 by means
of valves 25. It will be noted upon refer-
ence to Fig. 4 that the pipe 18 extends 95
throughout the length of the printing head
and that the branch pipes leading there-
from and being in communication with the
conduits 15 are connected at intervals
thereto. The valves 25 are located half way
100 between these branch pipes within the re-
gion of the closures or stops 17, and as is in-
dicated in Figs. 4 and 6, each valve is in
alinement with two opposing closures or
stops 17.

105 Referring to Fig. 4 and assuming that a
type sheet or web held upon the printing
head terminates at a point *a*, four valves 25
to the left of such point should be opened,
while those to the right thereof should be
110 closed. Three rows of type 30 are shown as
being secured to the type sheet 5, such type
being secured to the said sheet in known
manner.

115 33 designates abutments and guides, con-
sisting preferably of sponge rubber, which
are secured to the opposite sides of the
printing head frame adjacent the lower
edges thereof. The lower edges of these
120 abutments and guides 33 project below the
lower edges of the opposite sides 1 and 2
of the head and also below the lower or bot-
tom surface of the printing head pad 4.
The inner lower edges of the abutments and
guides 33 are beveled or flared outwardly as
125 indicated at 34 so that they may serve as
guides for the opposite edges of the type
sheet 5 as the latter, by the pressure of the
air when a partial vacuum is created inter-
mediate the said sheet and the adjacent op-
130

posing surface of the printing head pad 4, is caused to move toward the said pad. When the type sheet is in place against the underneath or bottom side of the said pad, opposite edges thereof contact with the inner beveled or flared surfaces 34 of the abutments and guides 33 and form air-tight joints therewith, thus assisting in preventing the passage of air in between the pad 4 and the type sheet 5.

The platen upon which the sheet to be printed is placed comprises a top pad 35 of sponge rubber or other suitable material supported upon a flooring or sheathing 36 which in turn is supported upon a frame structure comprising opposite side portions, each side portion consisting of a channel member 40 and a couple of sills 41 and 42, preferably of wood. These three parts, 40, 20 41 and 42, are secured together by means of bolts 43 in known manner.

Adjacent the opposite edges of the rubber platen 35 I provide bead-like portions 45 which extend from end to end thereof. 25 The distance between these bead-like portions 45 is equal to the width of the music roll to be printed and also of the type sheet 5, so that when either is laid upon the platen, the opposite edges thereof contact 30 with the inner sides of the bead-like portions 45.

When it is desired to print data of whatever character desired upon a music sheet the latter is placed in proper position upon 35 the platen and secured in such position in a manner which will be hereinafter described. It may be noted that the bead-like portions 45 are provided at one end or adjacent one end with a mark to indicate the 40 position in which the music sheet should be placed upon the platen. After a sheet has been placed and secured upon the platen the type sheet 5 upon which the type have already been secured is placed in position 45 thereon with the type in the proper position thereon to print the data desired at the proper points and places upon the music sheet.

In order to insure that the opposite edges 50 of the type sheet will enter within the lower flared inner edge portions of the abutments and guides 33 when the type sheet is resting upon the platen and when the printing head is lowered into adjacent relation or position 55 with respect thereto, I place cords 48 or similar means upon the top of the platen or upon a music sheet which may be thereon adjacent the inner sides of the bead-like portions 45. When the type sheet is laid upon 60 the said platen the opposite edge portions thereof rest upon these cords so that the said sheet will present a bowed appearance in cross section, as is indicated in Fig. 1 of the drawings. The result of this is to decrease 65 the distance between the opposite edges of

the type sheet and thus insure that they will enter between the opposite edge portions of the members 33 which constitute guides and abutments as above described. As soon as the type sheets 5 have been pressed up 70 against the under side of the pad 4 by the action of the atmosphere the cords 45 are removed. These cords or similar devices are used or employed only in connection with the attachment or securing of a type 75 sheet to the printing head, as above described.

In the operation of placing a music sheet upon the platen of the machine preferably two persons should be employed, one at 80 what may be termed the front of the machine, and the other at the opposite end or end portion thereof. The person at the front of the machine places the sheet in proper position as determined by the mark 85 or guide upon some portion of the platen structure, as for instance upon either or both of the bead-like portions 45 or some other portion of the said platen structure. The person at the opposite end or end portion of the machine takes hold of the opposite ends of the music sheet and pulls the same out straight and flat, in which position it should be secured. As a means for securing and holding the music sheet 90 stationarily upon the platen, I provide vacuums or partial vacuums at intervals upon the under side of the music sheet. One of these vacuums as indicated in Fig. 6 should be adjacent one end of the platen, while 100 such vacuum may be produced at a number of places at the opposite end portion of the said platen, the said places or points being situated in proper relation to the stops or closures 17 in the conduits 15. For the purpose of providing these vacuums or partial vacuums I have provided a pipe 50 having connection with the vacuum pump or other vacuum producing means previously referred to (the said connection and vacuum 105 pump or other vacuum producing means not being shown). The pipe 50 may be connected to the pipe or tube 18, the connection however not being shown. The exhausting of the air from the pipe 50 is controlled by means of a valve 51 situated adjacent the front end of the platen. The pipe 50 is provided with a laterally projecting branch tube 52 which by means of a length of rubber hose 53 is placed in communication with the lower end of a pipe 54, the upper end of which terminates in a flat circular nozzle 55 having holes 56 in its upper side, as shown. This nozzle is seated in an opening 57 formed within the rubber 110 platen 35. The top surface of the nozzle 55 is flush with the top surface of the rubber platen 35. The said nozzle rests upon the upper side of a sponge rubber pad 60 seated in an opening 61 in the flooring or sheath- 115

ing 36 of the platen structure. The purpose of supporting the nozzle 55 upon the sponge rubber pad 60 is that during the printing operation and when the printing head is moved down into position upon the music sheet to print thereon the nozzle will yield in the same way as the rubber platen 35 will yield.

At the opposite or rear end portion of the platen structure similar nozzles are provided, as indicated in Fig. 6 of the drawings, to which the rear end of the pipe 50 is adapted to be connected by means of a rubber or similar hose 65. This rubber hose can be connected to any one of a number of these nozzles as may be necessary to accommodate or correspond to the different lengths of music sheets which are being printed.

In Fig. 4 the rubber hose 65 is shown as connected to a nozzle in position to create a vacuum or partial vacuum underneath the music sheet 66 adjacent its rear end portion, the said sheet terminating a distance from the end of the platen structure, as is indicated in said figure. The moment that the sheet is in proper position upon the platen the operative at the front of the platen turns the valve 51 to permit the creation of a vacuum or partial vacuum within the pipe 50 and in the branches leading therefrom so as to create vacuums or partial vacuums, at a couple of points at least intermediate the top surface of the rubber platen and the bottom surface of the music sheet resting thereon. The music sheet will be held in position until the vacuum or partial vacuum is destroyed by closing the valve 51.

The purpose of employing sections of flexible tubing for connecting the pipe or tube 18 with the pipes 20, the lower ends of which are supported within the passageways 24 through the opposite sides 1 and 2 of the printing head structure, is to permit limited yielding movement of the pipe 18 toward one side or the other, due to vibration, without affecting the printing head structure and without putting unnecessary stress or strain upon the pipes 20. In other words the presence of the flexible rubber hose sections or connections 22 prevents unnecessary strain and injury upon and to the parts of the machine due to the vibration which is present during the use of the machine or press in the printing operation.

The branch pipes or connections between the central main exhaust pipe 18 and the conduits 15 are located at intervals as shown in order that the air may be exhausted uniformly from the said conduits 15 to thereby insure the holding of the type sheets closely against the underneath surface of the printing head sponge rubber pad at all points

throughout the length thereof. This insures against sagging of the type sheet away from the printing head pad. It is necessary to prevent sagging of the type sheet in order to prevent contact thereof with the inking pad. If the said type sheet should sag and should contact with the inking pad it is not only possible but probable that an ink splotch would be formed upon the music sheet in the printing operation and the latter be thus injured or perhaps rendered useless.

It is also apparent that by the employment of vacuum producing means for holding the type sheet upon the underneath side of the printing head pad in the manner as shown and described above, the said type sheet may be cut or divided into sections, if necessary or desired, the adjacent ends of the said sections being placed in abutting relation. This may become necessary in case the type sheets should expand and become too long by reason of the absorption of moisture or from any other cause. In such a case a necessary portion may be removed in order to adjust the type to the music sheet and insure the printing on the latter at the particular points or places as desired and as may be necessary.

It will be understood that the printing head may be divided into two or more sections which may be operated together or in unison as a single head, or each of the said sections may be operated independently of the other. In such case the exhaust pipe 18 would likewise be divided into sections and the adjacent opposing ends of such sections would be connected by means of flexible tubing so as to permit relative movement between the said pipe or tube sections.

It will be seen from the foregoing that I have provided a unitary printing press structure provided with means whereby the type sheet may be quickly placed in position against the bottom surface of the printing head and held against the same by the air pressure, and also whereby the music sheet may be quickly and readily attached and held to or upon the platen of such press. It will also be seen that I have provided a structure having means whereby type sheets of different lengths may be readily attached to and held upon the printing press platen.

Having thus described my invention, what I claim and desire to secure by Letters Patent, is:

1. In a printing press, the combination of a printing head having a type sheet supporting surface, abutments situated at the opposite lower edges of said head and projecting below the type sheet supporting surface,

a type sheet, and means for holding the said sheet against said surface with its opposite edges in abutting relation to said abutments.

2. In a printing press, the combination of 5 a printing head having a type sheet supporting surface, abutments situated at the opposite lower edges of said head and projecting below the type sheet supporting surface, a type sheet, and pneumatic means for 10 holding said sheet against the said type sheet supporting surface with its opposite edges in contact with said abutments.

3. In a printing press, the combination of 15 a printing head having a cushion upon its lower side against which a type sheet is adapted to be supported, said cushion having transversely extending grooves in its lower surface which terminate in grooves adjacent the opposite edges of said cushion, a type 20 sheet adapted to be supported upon said cushion over the said grooves, and means for exhausting the air from the said grooves whereby the said type sheet is held in place upon the said cushion by atmospheric pressure.

4. In a printing press, the combination of 25 a printing head, the lower surface of which is provided with transversely extending grooves and with longitudinally extending 30 grooves, the latter being situated adjacent the opposite edges of said head and the transverse grooves terminating therein, and the said head having longitudinally extending conduits therein which are in communication at intervals with the said longitudinally extending grooves, a type sheet adapted 35 to be supported upon the lower side of said head over transversely and longitudinally extending grooves, and an air exhaust 40 pipe for exhausting air from the said conduits and grooves whereby said type sheet is held in place by atmospheric pressure.

5. In a printing press, the combination of 45 a printing head, the said head being provided with groups of transversely and longitudinally extending grooves upon its lower surface, the longitudinally extending grooves being situated adjacent the lower opposite edges of the said head, and the 50 said transversely extending grooves terminating therein, conduits extending longitudinally of the said head, the said conduits being in communication with the said longitudinally extending grooves, a type sheet 55 adapted to be supported upon the lower side of the said head over the said grooves, and means for exhausting the air from both the transversely and longitudinally extending grooves.

6. In a printing press, the combination of 60 a type head provided upon its lower surface with groups of transversely and longitudinally extending grooves, the latter being situated adjacent the opposite lower edges of the said head, and the transverse-

ly extending grooves terminating therein, a type sheet adapted to be supported upon the lower side of the said head over the said grooves, an air exhaust pipe, and means for establishing communication between the 70 said exhaust pipe and the said grooves, the said means being situated at intervals whereby air may be exhausted from the said grooves when a type sheet is in position thereover.

7. In a printing press, the combination of 75 a printing head provided with a plurality of yielding pads upon its lower side, the said pads being arranged end to end, each pad being provided with transversely and longitudinally extending grooves, the latter being situated adjacent the opposite edges and the transversely extending grooves terminating therein, longitudinally extending 80 conduits situated within the opposite side portion of said head, the said conduits being in communication with the longitudinally extending grooves in the said pads, a type sheet adapted to be supported upon the said pads over the said grooves, and means for 85 exhausting air from the said conduits and from the said grooves whereby the said type sheet is held in place upon the said pads by external air pressure.

8. In a printing press, the combination of 90 a printing head having transversely and longitudinally extending grooves in its lower surface, the longitudinally extending grooves being situated adjacent the opposite edges of the said head and the transversely 95 extending grooves terminating therein, conduits extending longitudinally of the said head, said conduits having communicating connection at intervals with the said longitudinally extending grooves, a type sheet 100 adapted to be supported upon the lower side of said head over the said grooves, a relatively stationary air exhaust pipe supported upon said head, and flexible connections between the said air exhaust pipe and the said 105 conduits for exhausting air from the latter and from the said transversely and longitudinally extending grooves whereby the said type sheets are held upon the said head by atmospheric pressure.

9. In a printing press, the combination of 110 a printing head having abutments of yielding material secured to the opposite sides thereof, the lower inner sides of said abutments being flared outwardly, a type sheet adapted to be supported upon the lower side of said head, and means for holding said type sheet against the lower side of said head with its opposite edges in sealing contact with the opposite outwardly flared 115 lower edge portions of the said abutments.

10. A printing press, comprising a printing head having vacuum producing means for holding type sheets of different lengths upon the said head, the said vacuum means 120

including conduits, portions of which are provided with closures to divide the said conduits into non-communicating sections.

11. In a printing press, the combination of 5 a printing head having one or more conduits extending longitudinally thereof, an air exhaust passageway in communication at intervals with the said conduits, and means for closing the said conduits to divide the 10 same into sections whereby type sheets of different lengths may be held upon the said printing head.

12. In a printing press, the combination of 15 a printing head having one or more conduits extending longitudinally thereof, and the said printing head being also provided with passageways leading from the bottom surface thereof to the said conduits, an air exhaust passageway, including passageways 20 situated at intervals and connecting the said air exhaust passageway with the said conduits or conduits, and means for closing both the said passageway and the said conduits at corresponding points to regulate 25 the portions of the said conduit from which air shall be exhausted, substantially as described.

13. In a printing press, the combination 30 of a printing head having type sheet abutment and guiding members secured to the lower opposite side portions thereof, the lower edges of the said members projecting below the lower side of the said printing head and the lower inner side portions of 35 said members being flared outwardly, a platen with which the said printing head is adapted to co-operate, cords adapted to be placed on the said platen at the opposite edges thereof, a type sheet adapted to be 40 laid upon the said platen with the opposite edges thereof supported in elevated position upon the said cords, the distance between the said opposite edges being thereby decreased whereby, as the printing head is lowered 45 toward and upon the platen, the opposite edges of the said type sheet will enter the space between the said abutment and guiding members, and means for effecting movement of the said type sheet toward and for 50 holding it in position against the bottom surface of the said printing head.

14. In a printing press, the combination

of a printing head, a platen, a type sheet adapted to be supported upon said printing head, a sheet supported upon the platen upon 55 which the printing is to be effected, and pneumatic means for attaching and holding the type sheet and the said last mentioned sheet upon the printing head and platen respectively.

15. In a printing press, the combination 60 of a printing head, a type sheet adapted to be attached to and held upon the said printing head, a platen with which the said printing head is adapted to co-operate, 65 said platen being adapted to support a sheet which is to be printed upon, means for creating vacuums between the type sheet and the printing head and between the platen and the said second named sheet whereby 70 the said sheets are held in place upon the head and platen respectively by atmospheric pressure.

16. In a printing press for printing music 75 sheets for player pianos, the combination of a printing head, a type sheet adapted to be supported upon the said head, a platen adapted to support a music sheet for player pianos, and vacuum producing means for holding type and music sheets of different 80 lengths upon the said printing head and platen respectively.

17. A printing press for printing music 85 sheets for player pianos, comprising a platen adapted to support a music sheet for player pianos, an air exhaust pipe, means having connection with the said air exhaust pipe whereby a vacuum may be created between the said platen and the music sheet 90 thereon adjacent the front end portion of the said platen, and a plurality of means toward the opposite end portion of the said platen, any one of which is adapted to be connected to the said air exhaust pipe whereby a vacuum may be created between the said platen and the rear end portion of a music sheet thereon, whereby music sheets of different lengths may be secured and held upon said platen.

95 In testimony that I claim the foregoing 100 as my invention, I have hereunto subscribed my name this 22nd day of December, A. D., 1920.

GEORGE FUSSELL.
